UNITED STATES PATENT OFFICE

ERNEST M. ORLOW, OF WAUWATOSA, WISCONSIN

SLEEVE CONSTRUCTION FOR COATS

Application filed June 27, 1927. Serial No. 201,628.

This invention relates to sleeve constructions for coats.

The sleeve head of a coat is required to be puffed to get the rounded shape and necessarily requires a padding of some sort or some means for retaining this shape. The usual practice is to provide a thick padding roughly of crescent shape and secured within the head of the sleeve and lashed to the shoulder lining of the garment.

It has been found that this padding soon gets out of place, wrinkles or collapses, or otherwise loses its resiliency and effectiveness and the coat sleeve consequently presents an unsightly appearance.

This invention is designed to overcome the defects noted above and objects of such invention are to provide a novel form of sleeve construction for coats which prevents the head of the sleeve from getting out of shape and maintains its puffed or rounded formation, irrespective of the length of service.

Further objects are to provide a sleeve construction which may be most easily secured to the sleeve while the sleeve is in the process of formation and prior to its insertion in the arm hole of the coat, and to so form the sleeve that it will retain its shape throughout the life of the garment.

Further objects are to provide a novel form of sleeve construction which lends itself admirably to commercial or quantity production, which is very cheap, and which may be quickly produced.

An embodiment of the invention is shown in the accompanying drawings in which:

Figure 1 is a fragmentary view of the upper end of a sleeve;

Figure 2 is a sectional view on the line 2-2 of Figure 1.

Referring to the drawings, it will be seen that the sleeve comprises a body portion 1 and a rounded upper portion 2. It is provided with a marginal part 3 adapted for attachment to the arm hole of the body of the coat.

In order to retain the sleeve against loss of shape at the rounded head 2 a jute, hair cloth, or similar stiffener 4, of resilient fabric is employed and is shaped to the rounded

contour of the sleeve and positioned on the inner side, as shown in both figures of the drawing. This stiffener 4 is secured in place by a plurality of curved lines of stitching 5. The stitching is, however, blind stitching and does not show on the outer side of the sleeve. In addition to this, a non-resilient tape 6 is stitched around the marginal portion 3 of the sleeve just inside of its edge. This tape prevents elongation of the periphery of the opening in the sleeve and enhances the action of the stiffener.

It is preferable to place the stiffener with the weave diagonal, as shown in the drawings, although this is not absolutely essential. The stiffener is readily shaped to the curved contour and when sewed by the blind stitching securely in place to the inner side of the sleeve, it has been found that it will retain the shape of the upper or head of the sleeve throughout the life of the garment.

It is to be noted also that the construction is very simple and readily lends itself to quantity production. It is an easy matter to insert and secure the stiffener within the sleeve prior to the attaching of the sleeve to the body of the coat. This operation is very much simpler than the usual padding operation heretofore employed. In addition to this, the stiffener prevents creasing, breaking, or loss of shape of the sleeve and preserves the curved contour indefinitely.

Although the invention has been described in considerable detail, such description is intended as illustrative rather than limiting as the invention may be variously embodied and as the scope of such invention is to be determined as claimed.

I claim:

A sleeve construction for coats comprising a body portion provided with an arm hole and having a curved bulged head adjacent the arm hole and merging into the body portion of the sleeve, a stiffener formed of resilient fabric, shaped to the curved head of the sleeve and confined entirely within said sleeve, said fabric having its weave arranged diagonally to the axis of the sleeve and a plurality of distinct and separate rows of blind stitching securing the stiffener to the

fabric of the sleeve throughout the major portion of the stiffener, said rows of stitching being curved and converging at the front and rear of the sleeve.

5 In testimony that I claim the foregoing I have hereunto set my hand at Milwaukee, in the county of Milwaukee and State of Wisconsin.

ERNEST M. ORLOW.
